[57] CLAIM

The ornamental design for a bow string release, as shown.

DESCRIPTION

FIG. 1 is a top view of the bow string release according to the present invention;

FIG. 2 is a side view thereof;

FIG. 3 is a end view thereof;

FIG. 4 is an perspective view of the bow string release showing the intended configuration with respect to a bow string;

FIG. 5 is a side view of the bow string release showing the intended configuration of its use with respect to a bow, a bow string attached to the bow, a hand held bow string drawing device having an arrow release trigger, and an arrow;

FIG. 6 is an enlarged side view of the bow string release in the configuration of its intended use as shown in FIG. 5; and, FIG. 7 is an enlarged side view of the bow string release in the configuration of its intended use as in FIG. 6, except that the bow string release is not engaged with the hand held bow string drawing device.

The broken line showing of a bow string, a bow, a bow string drawing device, an arrow release trigger, and an arrow, in FIGS. 4-7 is for illustrative purposes only and forms no part of the claimed design.
